DRILLING BIT

Clifford R. Athy, Columbus, Ohio, assignor to The
Pure Oil Company, Chicago, Ill., a corporation
of Ohio

Application December 3, 1937, Serial No. 177,959

7 Claims. (Cl. 255—63)

This invention relates to method and means for locking and sealing separable devices and particularly to method and means for locking and sealing together multipart drilling bits used in 5 percussion well drilling operations.

Drilling bits commonly used in oil well drilling operations are made in one piece with the upper end or pin tapered and threaded to enable it to be screwed into the stem of the drilling string. 10 The blade of the bit becomes dull very rapidly when in use, necessitating frequent removal from the hole, and dressing. The withdrawal of the tool from the hole and the removal of the bit from the stem is a time consuming and laborious 15 operation.

Because of the fact that the blade becomes quickly dulled while in use, it is necessary to provide a forge on the derrick floor of the drilling operation where the blade can be reheated and 20 dressed in order to make it available for further use. Because the heat treatment at the derrick is rather crude and uncontrolled, it has been possible heretofore to use only plain carbon steel in the manufacture of bits. The use of high grade 25 alloy steels has been prohibitive due to the fact that such steels require careful heat treatment.

Not only have drilling operations been limited by the fact that it has been necessary to use low grade steels and to remove the drilling bit frequently from the hole, but the great weight of the bit has made very difficult its removal, and replacement on the drilling stem. 30

One object of my invention is to provide method and means for locking and sealing together parts 35 which must be frequently separated.

Another object of my invention is to provide a drilling bit of such nature that it will increase the speed of well drilling.

Still another object of my invention is to provide 40 a drilling bit which can be made out of high grade alloy steel.

A further object of my invention is to provide a drilling bit made in several parts so that only 45 the blade need be removed for dressing.

A further object of my invention is to provide a drilling bit of such nature that the portion thereof which requires dressing is made sufficiently light and sufficiently cheap to enable the 50 operator to keep a large supply thereof on hand and to enable the operator to return the blades at low cost to the manufacturer for dressing.

Another object of my invention is to lessen the labor involved in well drilling operations.

A still further object of my invention is to provide 55 a multi-piece bit which will effectively resist the forces and stresses to which it is subjected in operation without coming apart or breaking.

Other objects of my invention will be apparent 60 from the following description considered in con-

junction with the accompanying drawings, of which,

Fig. 1 is a diagrammatic elevational view of a 5 drilling bit made in accordance with my invention.

Fig. 2 is a cross-sectional view of the bit taken along the line 2—2 of Fig. 1.

Fig. 3 is a diagrammatic elevational view of the shank end of the bit shown in Fig. 1.

Fig. 4 is a plan view of the bottom of the shank 10 end shown in Fig. 3.

Fig. 5 is a diagrammatic elevational view of the blade end of the bit shown in Fig. 1.

Fig. 6 is a plan view of the top of the blade end 15 shown in Fig. 5.

Fig. 7 is a horizontal cross-sectional view similar to Fig. 2, showing a modified form of bit.

Fig. 8 is a vertical fragmentary cross-section showing a modified form of pin structure.

Fig. 9 is a vertical fragmentary cross-section 20 showing another modified form of pin structure.

Fig. 10 is a cross-sectional view of a modified form of pin.

Fig. 11 is a perspective view of another modification 25 of the pin.

Referring to the drawings, Figures 1 to 6, the numeral 1 indicates generally a drilling bit having a shank 3 and a blade 5. The lower end 6 of the shank is formed with a recess 7, counterbored at its lower end 9. The shoulder 11 between the side 30 wall 13 of the recess 7 and the side wall 15 of the counterbore or socket 9 is tapered upwardly and inwardly for a reason to be subsequently described.

The shank has a transverse bore 17 extending 35 entirely therethrough, a short distance above the upper end 19 of the recess 7. The bore 17 is slightly tapered from one end to the other and is adapted to receive a plug 21 which can be snugly driven into the bore. The plug is preferably provided with a circumferential groove 22 intermediate the ends thereof. A narrow vertical passageway 23, located centrally of the shank, connects the bore 17 with the recess 7. Pins 25 40 and 27 extend horizontally into the recess 7 intermediate the top and bottom of the recess. The pins 25 and 27 may be forged integrally with the shank or they may be welded, threaded or shrink- or hammer-fitted into holes bored horizontally through the walls of the shank at diametrically opposite points. Although the pins are shown as being cylindrical, they may be any other suitable shape. The upper end of the shank is formed with the threaded pin 29 which is adapted to be

50 screwed into the stem of the drilling string. 55 The blade is formed with the cutting edges 31 along the bottom thereof and the serrations 32 along the sides thereof to engage fishing tools. The blade has a T-shaped extension 33 at the upper end thereof. The head 34 of the extension 60

is formed with the lugs 35 and 37 extending horizontally at diametrically opposite points. These lugs are shaped to be best adapted to interlock with the pins 25 and 27. The blade has a shoulder 39 between the extension 33 and the upper end 41 of the blade proper. The shoulder 39 is shaped to conform to the shape of the side walls 15 of the counterbore or socket 9, and is adapted to fit snugly therein to provide a seal against leakage of the sealing medium. The height of the shoulder should be such that when the upper face thereof abuts the lower face 6 of the shank, the lugs 35 and 37 will clear the pins 25 and 27 when the blade is rotated into locking position.

15 The recess 7 may assume any desired shape but preferably conforms to the general shape shown in Figures 2 and 4. As shown, the recess assumes the form of two tangential circles joined together by two spaced lines perpendicular to the 20 common tangent so that the width at the points of jointure is somewhat less than the diameter of the circles but sufficiently wide to accommodate the extension 33 of the blade.

As shown more clearly in Fig. 2, the recess is 25 preferably of sufficient width and length to just permit the head 34 of the extension 33 to pass beyond the pins 25 and 27. As shown, the head of the extension is relatively narrow compared to its length.

30 In assembling the bit, the extension 33 of the blade end is inserted in the recess 7 with the T-head turned in the position shown in Fig. 2. The extension is then inserted far enough so that the lower sides of the lugs 35 and 37 are above the upper sides of the pins 25 and 27. The blade is then rotated until the lugs 35 and 37 are directly above the pins 25 and 27. As shown in Fig. 2, the pins 25 and 27 are so located that when the blade is rotated so that the lugs 35 and 37 are 35 above the pins, the blade cannot be rotated any further since the lugs engage the side walls of the recess 7. The blade is then shimmed to its proper axial relationship with the shank, with the shoulder 39 fitted in the socket 9. The plug 45 21 is then removed and molten lead or other readily fusible metal or alloy, such as tin-lead alloys, is poured through the passageway 23 into the recess 7 until it is entirely filled. The plug 21 is then replaced and driven in place. When 50 the lead or other metal or alloy solidifies, it fills the spaces between the extension 33 and the recess 7, preventing the blade from turning. The bit is then ready for operation.

In assembling the bit prior to pouring in the 55 molten lead, the face or end 41 of the blade is not fitted tightly against the lower end or face 6 of the shank, thus providing slightly more space in the recess 7 than would be the case if the faces fitted snugly against each other. The shoulder fits in the socket sufficiently close to prevent the molten metal from running out. During the drilling operation, the impact between the bottom of the hole and the bit tends to drive 60 the blade into the recess of the shank thereby causing the solidified metal to pack more tightly in the recess and to make a firmer joint. The metal also packs into the groove 22 of the plug 17 thereby preventing the plug from being jarred 70 loose.

The solidified metal is maintained in the recess by the fit made between the shoulder 39 and the socket 9. The tapered shoulder 11 permits any solidified lead in the counterbored portion of the 75 shank to be forced upwardly into the main por-

tion of the recess and to be packed more tightly therein.

By providing a joint of this kind, the solidified metal prevents rotation of the blade in the shank to the unlocked position and the pins 25 and 27 5 prevent the blade from slipping out of the shank due to vertical or pulling stresses during the lifting or jarring-up of the bit.

When the blade becomes dull and requires replacement, it is merely necessary to remove it 10 from the hole and heat the joint between the blade and the shank in order to melt the metal, remove the tapered pin or plug 21, and rotate the blade to the unlocked position whereupon it can easily be removed. Since the blade is relatively 15 light in comparison to the total weight of the bit, it can easily be handled and shipped back to the factory where it can be properly heat treated and dressed.

In the modification shown in Fig. 7, the pins 25' 20 and 27' are removable and the recess 7' conforms in shape to the shape of the head 34' of the extension. The extension 33' is adapted to be slipped straight into the recess 7' and fit fairly snugly therein. After the blade and shank ends 25 are assembled, the pins 25' and 27' are placed in holes bored through the side walls of the shank end, and the bit sealed together with readily fusible metal or alloy as heretofore described.

Since, in this modification it is not possible to 30 rotate the blade in order to remove it from the shank, it is necessary to have removable pins. The pins may be held in place in any suitable manner. As shown in Fig. 8, this is done by providing an annular groove 43 in the holes in which 35 the pins 25' and 27' fit and providing the pins with circumferential grooves 45 and longitudinal grooves 47 extending from the circumferential groove to the inner end of the pin. The circumferential groove on the pin is located so that 40 when the pin is tightly driven in the hole in the side wall of the shank, the groove is in line with the annular groove 43 of the hole. When the sealing lead or alloy is poured into the recess 7', some of it will find its way through groove 47 into 45 the grooves 43 and 45, where it will solidify and seal the pin in the hole.

The pins 25' and 27' are provided with heads 49 of smaller diameter than the main body of the pin, and are recessed at 51 where the head joins 50 the main body of the pin in order to enable a tool to be applied to the pin to remove it from the hole when it is desired to change the blade.

As shown in Figures 9 and 11, the pin 25'' and 27'' are threaded into the hole. In this modification of the pin, the pin and hole are threaded and provided with grooves similar to those described in connection with Fig. 8. The head 53 of the pin is provided with a diametric recess 55 in order to enable the pin to be screwed in and out 60 of the hole.

Although I have shown pins of frustro-conical shape, other shapes may be used and other means for holding them in place may be used.

By providing a separate blade, the blade can 65 be made of high grade alloy steels which will maintain their cutting edge for considerably longer periods than ordinary carbon steel. These blades can be made relatively cheap and light thereby enabling the producer to keep on hand 70 a large supply so that the blades can be dressed at the factory instead of at the derrick floor. Furthermore, by providing a separate blade portion, it is possible to build a stem and shank portion in one piece thereby eliminating the neces- 75

sity of providing a separate shank which must be screwed into the stem. In such case the lower end of the stem would be formed in the manner described in connection with the shank. In the 5 accompanying claims, the term "shank" or "shank end" refers to structure in which the stem and shank are made in separate pieces or in one piece.

In my preferred construction, the extension on 10 the blade fits loosely with the recess of the shank in order to allow space for the sealing metal or alloy to flow into and solidify. The solidified sealing material acts as a cushion and thereby prevents direct contact between the metal of the 15 shank and blade end and reduces the amount of wear between the parts. My invention is not limited to the loose construction but is intended to cover any construction, whether the parts are loosely or snugly fitted together, in which the parts are 20 25 locking elements are sealed by means of a fusible metal or alloy.

It will be apparent that the passageway for pouring molten metal into the assembled bit may be located in the blade instead of the shank, but I prefer to have the passageway in the shank.

The specific bits shown and described are for purposes of illustration only and it is to be understood that the invention is not limited to these specific forms. The invention is intended to 30 broadly cover all constructions in which parts are intended to be joined together in interlocking arrangement with the joint sealed with a fusible material, and particularly to drilling bits in which the blade is formed as a separate part of the bit 35 and adapted to be interlocked with a shank and the interlocking parts sealed with fusible metal.

What is claimed is:

1. A drilling bit comprising a shank and a separate blade, an axial recess in the lower end of 40 said shank, projections extending from the side walls of said shank into said recess, an extension on the upper end of said blade, said extension having horizontally projecting lugs adjacent the upper end thereof, said extension being adapted 45 to be inserted in said recess and rotated therein so that said lugs interlock with said projections, the unoccupied space in said recess being filled with a readily fusible metal or alloy forming the only positive means of securing said projections 50 and lugs in interlocking engagement and a passageway from the exterior of the shank to said recess and a closure for said passageway.

2. A drilling bit comprising a shank and a separate blade, a long and narrow axial recess in 55 the bottom of said shank, a pair of pins extending horizontally from diametrically opposite points of the walls of the shank into the recess, intermediate the top and bottom thereof, a long, narrow axial extension formed on the top of said 60 blade, said extension having a pair of oppositely projecting lugs adjacent the top thereof, said recess being counterbored at the lower end to provide a socket to accommodate a shoulder formed on the lower end of said extension, the recess also 65 being adapted to accommodate the extension and permit partial rotation of the extension so that the lugs interlock with the projections, the unoccupied space in said recess being filled with a readily fusible metal or alloy forming the only positive 70 means of securing said pins and lugs in interlocking relationship, a passageway from the exterior

of the shank to said recess, and a closure for said passageway.

3. A drilling bit comprising separate shank and blade ends, an axial recess in the lower end of 10 said shank end, an axial extension on the upper end of said blade end, horizontally projecting lugs on said extension, said extension being adapted to fit upwardly into said recess, removable pins adapted to project horizontally through 15 holes in the walls of the shank end into said recess, and to support said lugs from directly below when the bit is assembled, the unoccupied space in said recess being filled with a readily fusible metal or alloy forming the only positive means of securing said lugs and pins in interlocking relationship and a passageway from the exterior of the shank to said recess and a closure for said passageway.

4. A drilling bit in accordance with claim 3 in which the pins are provided with means to enable 20 them to be sealed in the holes of the shank end by means of a readily fusible metal or alloy.

5. A drilling bit comprising separate shank and blade ends, an axial recess in the lower end of 25 said shank end; an axial extension on the upper end of said blade end, horizontally projecting lugs on said extension, said extension being adapted to fit upwardly into said recess, said recess being counterbored at the lower end to provide a socket to accommodate a shoulder formed on the 30 lower end of said extension, removable pins adapted to project horizontally through holes in the walls of the shank end into said recess and to support said lugs from directly below when the bit is assembled, the unoccupied space in said 35 recess being filled with a readily fusible metal or alloy forming the only positive means of securing said lugs and pins in interlocking relationship.

6. A drilling bit comprising separable shank 40 and blade elements, said elements having an extension on one element and a recess on the other, said recess being adapted to receive said extension and being counterbored at the lower end to provide a socket to accommodate a shoulder 45 formed on the lower end of said extension, each element being provided with means to interlock with the other when the elements are assembled and the unoccupied space in said recess filled with a readily fusible metal or alloy forming the 50 only positive means of securing the interlocking means in interlocking relationship.

7. A drilling bit comprising a shank and a separate blade, an axial recess in the lower end of 55 said shank, projections extending from the side walls of said shank into said recess, an extension on the upper end of said blade having projecting lugs adjacent the upper end thereof, said recess being counterbored at the lower end to provide a socket to accommodate a shoulder formed on 60 the lower end of said extension, the recess also being adapted to accommodate the extension and permit rotation of the extension so that the lugs interlock with the projections, the unoccupied space in said recess being filled with a readily 65 fusible metal or alloy forming the only positive means of securing said lugs and projections in interlocking relationship and a passageway from the exterior of the shank to said recess and a closure for said passageway.

CLIFFORD R. ATHY.
